(57) **CLAIM**

The ornamental design for the “wall rack”, as shown and described.

DESCRIPTION

FIG. 1 is a perspective view of a wall rack made in accordance with the present invention;

FIG. 2 is a perspective view of the wall rack of FIG. 1 shown in use;

FIG. 3 is a front view of the wall rack of FIG. 1;

FIG. 4 is a back view of the wall rack of FIG. 1;

FIG. 5 is a top view of the wall rack of FIG. 1;

FIG. 6 is a bottom view of the wall rack of FIG. 1;

FIG. 7 is a right side elevation view of the wall rack of FIG. 1; and,

FIG. 8 is a left side elevation view of the wall rack of FIG. 1.

The broken lines show portions of the wall rack that form no part of the claimed design.

1 Claim, 8 Drawing Sheets
